UNITED STATES PATENT OFFICE.

JOHN E. BELL, OF NEW YORK, N. Y., ASSIGNOR TO THE BABCOCK & WILCOX COMPANY,
OF NEW YORK, N. Y., A CORPORATION OF NEW JERSEY.

WATER-TUBE BOILER.

1,070,391.

Specification of Letters Patent. Patented Aug. 19, 1913.

Application filed November 7, 1905. Serial No. 286,184.

To all whom it may concern:

Be it known that I, JOHN E. BELL, of the city of New York, State and county of New York, have invented certain new and 5 useful Improvements in Water-Tube Boilers, of which the following is a full, clear, and exact description, reference being had to the accompanying drawings, forming part of this specification, in which—

10 Figure 1 is a side elevation showing one form of boiler structure in accordance with my invention; Fig. 2 is a front elevation of the same; and Figs. 3 and 4 are views similar to Fig. 1, showing other forms of the 15 invention.

My invention relates to water-tube boilers and especially to those of the horizontal type, wherein the tube-heating surface extends in a general horizontal direction, 20 usually between the horizontal plane and 45 degrees thereto. Heretofore, such type of boiler, of which the Babcock & Wilcox boiler and Heine boiler and the Root boiler are examples, the number of rows of tubes 25 has been limited by the restriction of flow through the headers, particularly the upper channel headers. The height of the boiler and the amount of heating surface must therefore be below certain well known limits. In such boilers the grate surface should 30 have a certain proportionate relation to the heating surface to give good efficiency; and increase in the grate surface should be accompanied by corresponding increase in the 35 heating surface, which, however, must be limited as above described.

My invention overcomes these difficulties, 40 and provides a horizontal water tube boiler of great capacity, while occupying a comparatively small amount of floor space. The invention consists in independently connecting one or more sets or rows of lower water tubes adjacent to the furnace to the steam and water-drum or drums, at 45 one or both ends, preferably the up-current ends; the tubes above these lower tubes having connection to the steam and water-drum or drums independent of the connection for the lower tubes. The up-currents 50 from the lower tubes, which are otherwise liable to be burnt out, are thus given a freer exit to the steam and water-space and are not choked back by mingling with 55 and passing through the water from the upper tubes. The invention further con-

sists in an improved arrangement of baffles which is suitable for any horizontal water tube boiler, though especially adapted to my improved boiler.

In the drawings, referring to the form 60 of Figs. 1 and 2, I show a horizontal water-tube boiler having a lower set of inclined tubes 2 and an upper set of inclined tubes 3. The lower tubes are connected at one end, (in this case the rear end) to vertically-extending headers 4, which may be of the ordinary zig-zag or serpentine type; and the upper ends of these headers are connected by pipes or nipples 5 to the saddle 6 of a steam and water-drum 7, which I 65 have shown as extending longitudinally of the boiler. The steam and water-drum, may, however, extend transversely of the 70 boiler and be located above either end; or more than one steam and water-drum may 75 be employed.

The upper set of tubes 3 is shorter than the lower set and at one end they are connected to vertical headers 8, which are connected by nipples 9 to a second saddle 10 80 of the steam and water-drum 7. The opposite ends of the tubes 3 are connected to vertical headers 11, having at their upper ends nipples 12 connecting to saddle 13. The headers 11 preferably extend downwardly far enough to receive all of the tubes 3 and are nipples at their lower ends to a lower corresponding set of headers 14 85 receiving the ends of the lower set of water tubes 2. The headers 11 may be arranged 90 to receive the ends of all the tubes of both sets.

I have shown two sets of grates 15 and 95 16, extending from the front and rear walls 17, 18, to a bridge wall 19, arranged transversely at an intermediate point. Fire-doors 20 are provided at both ends of the setting in the form shown, the grates extending underneath substantially the whole 100 of the boiler. The fire-doors may, however, be placed at one or both ends of the setting and the grates may extend beneath any desired portion or portions of the heating surface.

The baffling may be of any desirable 105 type. In the form of Figs. 1 and 2 I have shown a lower horizontally-extending baffle 21, lying on the lower row of water-tubes and another horizontal baffle 22 extending from the opposite end and lying 110

on the upper row of the lower set of tubes 2. At the end of the baffle 22 is a vertical baffle 23, leaving a gas port at its upper end, and a depending baffle 24 is preferably placed between the baffle 23 and the uptake 25. The flames and gases are thus given a tortuous course along and across the water-tubes.

The space between the headers 8 for the upper set of tubes 3 and the pipe connections 5 for the corresponding headers of the lower set of tubes is preferably large enough to allow entrance of a man through the side wall of the setting. For this purpose a door or doors 26 may be used in the side wall or walls, through which the man can enter to expand the tubes or remove and replace them.

In the operation of the boiler, the water and steam in the lower tubes flow into the headers 4 and thence through the pipe connections 5 directly into the steam and water-drum, where the steam is released. A rapid circulation may thus be provided in the lower set of tubes which is nearest the furnace and is most liable to be burnt out. This up-circulation of steam and water passes upwardly separate from the up-circulation of the tubes 3, the latter passing up through the headers 8 and nipples 9, and descending through the headers 11 and 14. I do not consider it necessary to employ separate connections for the two sets of tubes 2 and 3 at this end of the boiler. Separate headers and connections may, however, be used for the sets of tubes at one or both ends within the scope of my broader claims, although the main advantages of my invention flow from the separate connections at the up-current ends.

As the upper set of tubes is subjected to the furnace gases after they have parted with a portion of their heat, I can stack the rows of tubes of this upper set above each other to any desirable height within practical limits, without danger of burning out the lower tubes.

In Fig. 3, I show a form similar to that of Figs. 1 and 2, except that the baffling is somewhat different. In this form the baffling is entirely horizontally-extending, the upper horizontal baffles 27 and 27' being used in addition to the lower baffles 21^a and 22^a. The course of the gases will be somewhat different in this form, but otherwise is substantially the same as in the first form, the up-currents of water from the lower tubes passing through their own independent connections to the steam and water-drum.

In Fig. 4 I show a form similar to that of Fig. 1, except that the set of tubes 3 is inclined in the opposite direction to that of the lower tubes 2. In this case, where I have used similar numerals to those of Fig.

1, except with the letter "b" annexed thereto, the nipples 9^b are longer than nipples 12^b.

Instead of using two sets of tubes with separate connections to the steam and water-drum at one end, I may employ three or more sets, each set preferably having its own independent connection to the steam and water-drum or drums at one end, or both ends, if desired.

The advantages of my invention result from the separate connection of the lower tubes with the steam and water-space; since thereby the amount of heating surface and grate surface can be increased without increasing the floor space and without liability of burning out the lower tubes. A rapid circulation may take place through these lower tubes, since the up-currents of this up-circulation pass directly to the steam and water-drum or drums. The upper set or sets of tubes may be stacked up to any desirable height, since there is little or no danger of burning out such tubes. A very large amount of heating surface may thus be provided and the grate surface may be made correspondingly large by increasing the grate area even to covering substantially the whole of the floor space occupied. The baffling, by a horizontal pass among the tubes, followed by vertical passes, gives efficient extraction of heat.

Instead of the ordinary headers at the ends of the tubes, I may employ a water leg or legs such as in the Heine type of boiler, or I may use boxes or manifolds of any desired shape or size. The tubes may be divided into two or more sets and the upper set may act as an economizer or feed-water heater.

The upper set or sets of tubes may have the same inclination as the lower set of tubes, or may be inclined at a different angle, or reversely inclined. The furnace may be fired from one or both ends and the grate may extend below any part or all of the boiler. The separate connections for the sets of tubes may be used at either or both ends and any desired type of baffle may be used. Instead of having the pipes or nipples run directly from the headers or boxes to the steam and water-drum or drums, they may extend to an intermediate box, chamber or chambers, which in turn is connected to the steam and water-drum or drums. The lower baffle may be above one or more rows of tubes or supported below the lower-most row of tubes.

My invention may be applied to either marine boilers or boilers of the land type.

Many other variations may be made in the form and arrangement of the various pipes, without departing from my invention.

I claim:

1. A steam boiler having a steam and water

- drum, two banks of inclined tubes, one above the other, the tubes of the lower bank being longer than the tubes of the upper bank, headers connected to both ends of the tubes of both banks, circulating connections between the headers at one end of both banks and the drum, and circulating tubes connected to the headers at the other end of the lower bank of tubes and the drum, 10 said last-mentioned headers being the uptake headers of the lower bank, the cross sectional area of the circulating tubes connected to the uptake headers of the lower bank being less than the combined cross sectional area of the tubes of the lower bank, substantially as described.
2. A steam boiler having a steam and water drum, two banks of inclined tubes, one above the other, the tubes of the lower bank being longer than the tubes of the upper bank, headers connected to both ends of the tubes of both banks, the downtime headers of the lower bank being directly below the headers at one end of the upper bank, circulating tubes connected to said headers of both banks, circulating tubes to the headers of the upper bank and the drum, and circulating tubes connected to the headers at the uptake end of the lower bank and the drum, the cross sectional area of the last-mentioned tubes being less than the combined cross sectional area of the tubes of the lower bank, a longitudinally disposed baffle above the upper row of tubes of the lower bank, a longitudinally disposed baffle above the lower row of tubes of the lower bank, there being sufficient space between 20 said baffles to permit all of the products of combustion to pass longitudinally along the tubes of the lower bank, and a plurality of vertically disposed cross baffles for the upper bank of tubes, said baffles giving the gases three passes across said bank of tubes, substantially as described.
2. A steam boiler having a steam and water drum, two banks of inclined tubes, one above the other, the tubes of the lower bank being longer than the tubes of the upper bank, headers connected to both ends of the tubes of both banks, the downtime headers of the lower bank being directly below the headers at one end of the upper bank, circulating tubes connected to said headers of both banks, circulating tubes to the headers of the upper bank and the drum, and circulating tubes connected to the headers at the uptake end of the lower bank and the drum, the cross sectional area of the last-mentioned tubes being less than the combined cross sectional area of the tubes of the lower bank, substantially as described.
3. A steam boiler having a steam and water drum, two banks of inclined tubes, one above the other, the tubes of the lower bank being longer than the tubes of the upper bank, headers connected to both ends of the tubes of both banks, the downtime headers of the lower bank being directly below the headers at one end of the upper bank, circulating tubes connected to said headers of both banks, circulating tubes to the headers of the upper bank and the drum, and circulating tubes connected to the headers at the uptake end of the lower bank and the drum, the cross sectional area of the last-mentioned tubes being less than the combined cross sectional area of the tubes of the lower bank, a longitudinally disposed baffle above the upper row of tubes of the lower bank, and a longitudinally disposed baffle above the lower row of tubes of the lower bank, there being sufficient space between 30 said baffles to permit all of the products of combustion to pass longitudinally along the tubes of the lower bank, and a plurality of vertically disposed cross baffles for the upper bank of tubes, said baffles giving the gases three passes across said bank of tubes, substantially as described.
3. A steam boiler having a steam and water drum, two banks of inclined tubes, one above the other, the tubes of the lower bank being longer than the tubes of the upper bank, headers connected to both ends of the tubes of both banks, the downtime headers of the lower bank being directly below the headers at one end of the upper bank, circulating tubes connected to said headers of both banks, circulating tubes to the headers of the upper bank and the drum, and circulating tubes connected to the headers at the uptake end of the lower bank and the drum, the cross sectional area of the last-mentioned tubes being less than the combined cross sectional area of the tubes of the lower bank, a longitudinally disposed baffle above the upper row of tubes of the lower bank, and a longitudinally disposed baffle above the lower row of tubes of the lower bank, there being sufficient space between 40 said baffles to permit all of the products of combustion to pass longitudinally along the tubes of the lower bank, and a plurality of vertically disposed cross baffles for the upper bank of tubes, said baffles giving the gases three passes across said bank of tubes, substantially as described.
4. A steam boiler having a steam and water drum, two banks of inclined tubes, one above the other, the tubes of the lower bank being longer than the tubes of the upper bank, headers connected to both ends of the tubes of both banks, the downtime headers of the lower bank being directly below the headers at one end of the upper bank, circulating tubes connected to said headers of both banks, circulating tubes to the headers of the upper bank and the drum, and circulating tubes connected to the headers at the uptake end of the lower bank and the drum, the cross sectional area of the last-mentioned tubes being less than the combined cross sectional area of the tubes of the lower bank, a longitudinally disposed baffle above the upper row of tubes of the lower bank, and a longitudinally disposed baffle above the lower row of tubes of the lower bank, there being sufficient space between 45 said baffles to permit all of the products of combustion to pass longitudinally along the tubes of the lower bank, and a plurality of vertically disposed cross baffles for the upper bank of tubes, said baffles giving the gases three passes across said bank of tubes, substantially as described.
5. A water tube boiler having a steam and water drum, two banks of inclined tubes, one above the other and lying wholly within the casing, the tubes of the lower bank being of greater length than those of the upper bank whereby a space is left above the uptake end of the lower bank back of the uptake headers of the upper bank, headers 50 into which the ends of the tubes are expanded, the downtime headers of the two banks being nipped together or continuous and those of the upper bank connected to the water space of said drum, independent tubular connections from the uptake headers to said drum, a longitudinal baffle supported on the lowermost row of tubes of the lower bank and extending from the downtime header, a second longitudinal baffle supported upon the uppermost row of tubes of the lower bank and extending from the uptake header of said bank overlapping the lower baffle, whereby all of the products of combustion are caused to pass longitudinally 55 of the tubes of the lower bank, and transverse baffles dividing the upper bank into a plurality of transverse passes beginning at the downtime end, said tubular connections having a less cross sectional area than the combined cross sectional area of the tubes of the lowermost bank.
- In testimony whereof, I have hereunto set my hand,

JOHN E. BELL.
